Attorney

UNITED STATES PATENT OFFICE.

IRVIN G. WHITLOW, OF NILES, OHIO.

STOOL.

No. 904,034.

Specification of Letters Patent.

Patented Nov. 17, 1908.

Application filed March 10, 1908. Serial No. 420,205.

To all whom it may concern:

Be it known that I, IRVIN G. WHITLOW, a citizen of the United States, residing at Niles, in the county of Trumbull and State of Ohio, have invented new and useful Improvements 5 in Stools, of which the following is a specification.

My invention relates to stools, and its primary object is to provide a device of this 10 character which is especially adapted for use by motormen and in stores, and one wherein the seat is resiliently supported to prevent the vibrations of the car from being transferred to the occupant of the seat and to prevent 15 any chock incident to the initial occupancy of the seat.

A further object of my invention is the provision of a stool wherein the foot rest is adapted to limit the movement of the seat in 20 both directions.

A still further object of my invention is to provide a stool which is simple, durable and efficient, and which can be manufactured and sold at a comparatively low cost.

With the above and other objects in view, the invention consists in the construction, combination and arrangement of parts hereinafter fully described, claimed and illustrated in the accompanying drawing, where- 25 in:

Figure 1 is a view in side elevation of a stool constructed in accordance with my invention, portions of the tubular support and a portion of the post of the stool being in vertical section. Fig. 2 is a horizontal sectional view taken on a plane indicated by the line 2—2 of Fig. 1, looking in the direction indicated by the arrow, and Fig. 3 is a similar view taken on a plane indicated by the line 3—3 of Fig. 1, looking in the direction indicated by the arrow. Fig. 4 is a detail view of a modified form of the stem or bar and socket.

Referring to the drawing by reference 45 numerals, 1 designates a portion of the floor of a building or the platform of a car.

2 designates the vertical support, 3 the post and 4 the seat of my improved stool. The support 2 consists of a hollow cylindri- 50 cal member of suitable length, and its lower end is closed by means of a plug 5.

A stem or bar 6 is secured to the plug 5 and extends downwardly from the lower end of the support 2. The stem or bar 6 provides 55 means by which the support 2 is secured to the floor or platform, said stem or bar pass-

ing through a socket 7 let into the upper surface of the floor or platform. The socket 7 is provided with a horizontally disposed flange 8, and is secured in applied position 60 by means of screws 9 or their equivalents, which are let through said flange and entered into the floor or platform 1. The stem or bar 6 may be angular in cross-section as disclosed in Fig. 3 of the drawing, or circular in cross-section as disclosed in Fig. 4 of the drawing. The post 3 is slidably received by the support 2, and is provided at its lower end with an elongated vertical slot 10. An expansible spring 11 is mounted within the 70 support 2 between the plug 5 and the lower end of the post 3, said spring being adapted to yieldingly support the seat 4.

The movement of the seat 4 is limited in both directions by the horizontal bar 12 of 75 a foot rest 13, said bar passing transversely through the support 2 and through the slot 10 in the post 3. The bar 12 extends laterally beyond the support 2 in both directions, and the outer ends thereof are supported by 80 braces 14 which are formed integrally with the bar and which are secured at their lower free ends to the support by means of screws 15 or their equivalents. The seat 4 is secured to the post 3 by means of a hinge 16 to permit it to be thrown into a vertical position when not in use. As the seat 4 is supported by the spring 11, the stool is admirably adapted for use by motormen, said spring being designed to take up and absorb vibrations of the car. It should be apparent that the stool is also adapted for use in stores, the resilient supporting of the seat 4 preventing any jar incident to the initial occupancy of 90 the stool, and the hinging of the seat permitting it to be swung beneath the counter 95 out of the way when the stool is not in use.

From the foregoing description taken in connection with the accompanying drawing, the construction and mode of operation of 100 the invention should be understood without a further extended description.

Changes in the form, proportions and minor details of construction may be made within the scope of the claims without departing from the spirit or sacrificing any of 105 the advantages of the invention.

Having fully described and illustrated my invention, what I claim is:

1. A stool comprising a hollow support, a 110 post slidably received by the support and provided with a slot, a seat secured to the

post, a spring mounted within the support below the post, and a bar extending transversely through the support and slot, said bar being adapted to limit the movement of the post in both directions and to form a foot rest.

2. A stool comprising a support, a post slidably mounted on the support and provided with a slot, a seat secured to the post, 10 a spring carried by the support to sustain the post, and a foot rest secured to the support and passing through the slot in the post, said foot rest being adapted to limit the movement of the post in both directions.

15 3. A stool comprising a support, a post slidably mounted on the support, a seat secured to the post, a spring carried by the support to sustain the post, and a foot rest secured to the support, said foot rest being

connected with the post to limit the movement of the post in both directions. 20

4. A stool comprising a hollow support, a plug closing one end of the support, a stem secured to the plug, a socket, a post slidably received by the support and provided with a 25 slot, a seat secured to the post, a spring mounted within the support between the plug and the post, and a foot rest secured to the support and passing through the slot in the post, said foot rest being adapted to limit 30 the movement of the post in both directions.

In testimony whereof I affix my signature in presence of two witnesses.

IRVIN G. WHITLOW.
